Filed Feb. 20, 1962, Ser. No. 68,905

Term of patent 14 years

(Cl. D22—3)

FIGURE 1 is a perspective view of a steak knife or similar article showing my new design;

FIG. 2 is a side elevational view thereof;

FIG. 3 is a plan view thereof looking in the direction 3-3 of FIG. 2;

FIG. 4 is a plan view thereof looking in the direction 4-4 of FIG. 2;

FIG. 5 is an enlarged sectional view on the line 5-5 of FIGS. 2 and 10;

FIG. 6 is an enlarged sectional view on the line 6-6 of FIGS. 2 and 10;

FIG. 7 is an enlarged sectional view on the line 7-7 of FIGS. 2 and 10;

FIG. 8 is an enlarged sectional view on the line 8-8 of FIGS. 2 and 10;

FIG. 9 is a perspective view of a carving knife or similar article on the same scale as FIG. 1, incorporating a variant of the same ornamental design concept shown in FIGS. 1 through 8;

FIG. 10 is a side elevational view thereof on a reduced scale;

FIG. 11 is a plan view thereof looking in the direction 11-11 of FIG. 10; and

FIG. 12 is a plan view thereof looking in the direction 12-12 of FIG. 10.

The essential features of my design reside in the full line showings of the handles, which are integral with the respective blades shown in dashed lines. The design is generally characterized by integrally-formed handles having variably-concave sections at the end adjacent the blade and variably convex sections adjacent the other end.

I claim:

The ornamental design for a knife or similar article, substantially as shown and described.
